RESILIENT END BUFFER FOR RAILWAY
CARS AND LOCOMOTIVES

John W. Marsh, Alexandria, Va., assignor of one-fourth to Florence E. Marsh, one-fourth to Marianne Marsh, and one-fourth to Mary Marsh, all of Alexandria, Va.

Application November 9, 1944, Serial No. 562,655

5 Claims. (Cl. 213—221)

1

This invention relates to improvements in buffers for railway cars and locomotives.

It is among the objects of the present invention to provide a device of the class described which forms a unit assembly, without bolts, nuts or similar fastening devices.

Another object is to provide an arrangement of cooperating elements which is simplified as to construction and assembly.

These and other objects and advantages of my invention will become apparent upon a consideration of the following detailed description when taken in conjunction with the following drawings, in which

Fig. 1 is a sectional view of a buffer construction taken along the line 1—1 of Fig. 2 embodying the elements of the present invention.

Fig. 2 is a sectional view taken along the line 2—2 of Figs. 1 and 7.

Fig. 3 is a sectional view taken along the line 3—3 of Fig. 4 and showing a more detailed view of the buffer housing.

Fig. 4 is an end view of the buffer housing.

Fig. 5 is a side view of the buffer lock.

Fig. 6 is an end view of the buffer lock.

Fig. 7 is a sectional view of an alternate buffer construction taken along the line 1—1 of Fig. 2.

Fig. 8 is a side view of the alternate buffer lock.

Fig. 9 is an end view of the alternate buffer lock.

Referring to the drawings it will be seen that there is provided a cylindrical housing 1 on one end of which is formed a flange portion 2 suitable for attachment to the frame of a railway vehicle. The flanged end of the housing is closed by a plate having an undulated surface 3 (Fig. 3) towards the interior of the housing, the purpose of which will be explained hereafter. The open end of the housing has inwardly projecting lips 4, 5, 6, 7, formed thereon spaced uniformly around the inner periphery of the housing and extending over less than half of said inner periphery leaving spaces 8, 9, 10, 11, therebetween.

The buffer plunger is provided at its outer end with a buffering head 12 attached to a cylindrical portion 13, adapted to oscillate within the inner peripheries of lips 4, 5, 6, 7. The inner end of cylindrical portion 13 is provided with outwardly flaring sectors 14, 15, 16, 17, spaced uniformly around the periphery and adapted to oscillate within the cylindrical housing 1, and to pass through the spaces 8, 9, 10, 11.

The buffer lock 18, shown in more detail in Figs. 5 and 6, is provided with a base 19, having an inner surface 20 suitable for engaging a spring

2

24, and an outer surface 21 formed to the contour of undulated surface 3 (Fig. 3). The lock is provided with means cooperating with means on the plunger to hold the lock and plunger against relative rotational movement. In the construction illustrated, such means take the form of axial keys 22, 23 on the lock which are engageable with portions of projections 14, 15, 16, and 17 on the plunger. The plunger is free to move axially relative to the lock while the keys remain in engagement with the portions of the projections referred to.

The spring 24 is positioned within cylindrical portion 13, in a manner as to continually contact buffer head 12 and surface 20 of the buffer lock. The central portion of spring 24 is shown broken away in Fig. 1 to more clearly show the construction of the outwardly flaring sector 15.

It will be noted that the undulated surface 21 (Fig. 5) on buffer lock 18 is provided with depressions 25, 26, 27, 28, which correspond with and receive elevated portions 29, 30, 31, 32, respectively, on undulated surface 3 (Fig. 3), when the buffer is assembled with the keys 22, 23, fitted within the outwardly flaring sectors 14, 16 of the cylindrical portion 13, and with the outwardly flaring sectors 14, 15, 16, 17, abutting lips 5, 4, 7, 6. When the assembly of cylindrical portion 13 and lock 18 is rotated to permit the outwardly flaring sectors 14, 15, 16, 17, to correspond with spaces 9, 8, 11, 10, the elevated portions 29, 30, 31, 32, on surface 3 will abut the elevated portions 36, 33, 34, 35, of surface 21. This rotation will move lock 18 axially relative to the housing 1 and compress spring 24.

The assembly of the buffer is accomplished by inserting the assembly of cylindrical portion 13, spring 24 and lock 18 into the housing 1, the outwardly flaring sectors 14, 15, 16, 17, passing through spaces 9, 8, 11, 10, until the elevated portions 36, 33, 34, 35, on surface 21 abut the elevated portions 29, 30, 31, 32, on surface 3. Axial movement of the cylindrical portion 13 is continued, compressing spring 24, until the outwardly flaring sectors 14, 15, 16, 17, pass lips 5, 4, 7, 6, when the interior assembly is rotated within the housing 1 to the position shown in Fig. 1, until outwardly flaring sectors 14, 15, 16, 17 are aligned with lips 5, 4, 7, 6, and depressions 25, 26, 27, 28 receive elevated portions 29, 30, 31, 32.

Accidental rotation of the cylindrical portion 13 from its normally assembled position in the housing 1 is restrained by the engagement of the keys 22, 23, within the outwardly flaring sectors 14, 16, the rotation of the keys relative to the housing

1 being restrained by the spring compression maintaining the surfaces 3 and 21 in their mutually cooperative position.

An alternate construction is shown in Fig. 7, which uses the same buffer and housing as shown in Figs 1, 2, 3, 4, but in which the keys of the lock are arranged to fit between the outwardly flaring portions 14, 15, 16, 17, and between the cylindrical portion 13 and housing 1. In this alternate construction, keys 41, 42, of lock 43 are formed on base 44 opposite depressions 45, 47, so that when depressions 45, 46, 47, 48, receive elevated portions 30, 31, 32, 29, keys 41, 42, lie between outwardly flaring portions 14, 15, and 16, 17, respectively.

In assembly of the alternate construction, buffer lock 43 is inserted in housing 1, keys 41, 42, passing through spaces 9, 11, then rotated within housing 1 until the elevated portions 49, 50, 51, 52, abut elevated portions 30, 31, 32, 29, on surface 3 (Fig. 3). Spring 24 and cylindrical portion 13 are inserted in the housing, outwardly flaring portions 14, 15, 16, 17, passing through spaces 9, 8, 11, 10, and keys 41, 42, entering spaces 40, 38. The cylindrical portion 13 is inserted into case 1 until outwardly flaring portions 14, 15, 16, 17, pass lips 5, 4, 7, 6, compressing spring 24, when cylindrical portion 13 and lock are rotated until depressions 45, 46, 47, 48 receive elevated portions 30, 31, 32, 29, and outwardly flaring portions 14, 15, 16, 17, are coextensive with lips 5, 4, 7, 6.

Other modifications will suggest themselves to one skilled in the art, and it is understood that I do not wish to be limited to the particular details and arrangement disclosed but by scope of the claims.

I claim:

1. A buffer comprising an outer cylinder having one end substantially closed and having inwardly projecting shoulders at the opposite end, said closed end having an undulated surface facing the interior of the cylinder, an inner cylinder slidably disposed in said outer cylinder and adapted to project therefrom, said inner cylinder having a buffering head on its exposed end and radially projecting portions adjacent its end within the outer cylinder, said portions being substantially coextensive with the shoulders aforesaid and spaced at intervals permitting the passage of the latter therebetween, a key member positioned within said outer cylinder, comprising an elongated portion adapted to engage said radially projecting portions and a plate portion having an undulated surface adapted to cooperate crest to valley with said undulated surface on the end of said outer cylinder, when aforesaid radially projecting portions are substantially coextensive with said shoulders, and a resiliently compressible member positioned within the inner cylinder and abutting the plate portion of the key member and the buffering head of the inner cylinder.

2. A buffer comprising an outer cylinder having one end substantially closed and having inwardly projecting shoulders at the opposite end, the closed end of said outer cylinder having an undulated surface facing the interior of the cylinder, an inner cylinder slidably disposed in said outer cylinder and adapted to project therefrom, said inner cylinder having a buffering head at its exposed end and radially projecting portions adjacent its end within the outer cylinder, said portions being substantially coextensive with said shoulders and spaced at intervals permitting the passage of the latter therebetween, a key member positioned within said outer cylinder comprising a

plurality of elongated portions adapted to engage said radially projecting portions on the inner cylinder, and a plate portion having an undulated surface adapted to cooperate crest to valley with said undulated surface on the interior of the closed end of the outer cylinder, when said radially projecting portions are substantially coextensive with the shoulders on the outer cylinder, and a resiliently compressible member positioned within the inner cylinder and abutting the plate portion of the key member and the buffering head of the inner cylinder.

3. A buffer comprising an outer cylinder having one end substantially closed and having inwardly projecting shoulders at the open end, the outer cylinder having an undulated surface on its closed end facing the interior of the cylinder, an inner cylinder slidably disposed in said outer cylinder and adapted to project therefrom, the inner cylinder having a buffering head on its exposed end and radially projecting portions adjacent its end within the outer cylinder, said portions being substantially coextensive with the shoulders on the outer cylinder and spaced at intervals permitting the passage of the latter therebetween, a key member positioned within said outer cylinder, comprising an elongated portion adapted to engage radially projecting portions on the inner cylinder, and a plate portion having undulated surface adapted to cooperate, crest to valley, with the undulated surface formed on interior of the closed end of the outer cylinder, when the radially projecting portions on the inner cylinder are in alignment with the shoulders on the outer cylinder and to abut, crest to crest, with the undulated surface on the closed end of the outer cylinder, when said radially projecting portions are aligned with the intervals between the shoulders, and a resiliently compressible member positioned within the inner cylinder and abutting the plate portion of the key member and the buffering head on the inner cylinder.

4. A buffer comprising a housing having one end substantially closed and provided at its open end with circumferentially spaced inward projections, a hollow plunger mounted in the housing for sliding movement within the projections and having a portion extending out of the housing, the exposed end of the plunger being closed, the portion of the plunger within the housing having circumferentially spaced outward projections behind and aligned with the projections on the housing, the projections on the plunger being adapted, upon relative rotation of the housing and plunger, to be passed between the projections on the housing, a key member within the housing, the key member and plunger having interengaging means preventing relative angular movement of the plunger and member while permitting their relative axial movement, interengaging means on the key member and on the housing adjacent its closed end operable to resist relative rotation of the key member and housing, and spring means within the housing and plunger engaging at one end the closed outer end of the plunger and, at the other end, a portion of the key member, said spring means acting to hold the interengaging means on the key member and housing in operative relation, whereby the projections on the plunger are maintained in alignment with those on the housing.

5. A buffer comprising a housing having one end substantially closed and provided at its open end with circumferentially spaced inward pro-

jections, a hollow plunger mounted in the housing for sliding movement within the projections and having a portion extending out of the housing, the exposed end of the plunger being closed, the portion of the plunger within the housing having circumferentially spaced outward projections behind and aligned with the projections on the housing, the projections on the plunger being adapted, upon relative rotation of the housing and plunger, to be passed between the projections on the housing, a key member within the housing having an end portion seated against the closed end of the housing, the key member and plunger having interengaging means preventing relative

angular movement of the key member and plunger while permitting their relative axial movement, interengaging means on the key member and on the housing adjacent its closed end operable to resist relative rotation of the key member and housing, and spring means within the housing and plunger confined between the closed outer end of the plunger and the end portion of the key member, said spring means acting to hold the interengaging means on the key member and housing in operative relation, whereby the projections on the plunger are maintained in alignment with those on the housing.

JOHN W. MARSH.
